APPARATUS FOR TREATING CRUDE PETROLEUM AND OTHER LIQUIDS

Floyd A. Kent and Clarence W. Patrick,
Midland, Mich.

Application March 3, 1947, Serial No. 732,108

4 Claims. (CL 233—21)

1

This invention relates to apparatus for treating liquids such as crude petroleum as it is pumped from wells, and more particularly to an apparatus designed to separate liquids of different specific gravities such as oil from the brine, sludge and other impurities, and to separately drain off the oil and also the separated brine and impurities found therein, so that it does not interfere with or retard the cracking and final refining of the product.

One of the prime objects of the invention is to design an apparatus, including a tank or basin, into which the crude petroleum is pumped, and from which it is forced into a driven separator for agitating and separating the oil, brine, and other impurities which are taken off at different levels or zones, as the apparatus is operated.

Another object is to provide a petroleum treating apparatus in which the crude petroleum is inserted at the lower end of the apparatus and is then rotated, so that centrifugal force causes the more volatile oil to rise and overflow, after it has reached a predetermined level, the brine, impurities, etc., due to the difference in specific gravities, being forced outwardly towards the outer wall of the shell and are then drained off in a similar manner.

A further object is to design simple, practical, and efficient apparatus, including means for effectively separating the oil from the brine and impurities, together with means for driving said shell to force the crude petroleum into the shell as the apparatus is operated.

A further object still is to provide petroleum treating apparatus including a driven shell having scoops extending into the liquid to be treated, so that the pressure generated by the shell rotation forces the liquid upwardly into the shell, where it is separated by centrifugal action and then drawn off into separate tanks or containers.

To the accomplishment of the foregoing and related ends, said invention then consists of the means hereinafter fully described, and particularly pointed out in the claims, the annexed drawings and following description setting forth, in detail, certain means and one mode of carrying out the invention, such disclosed means and mode illustrating, however, but one of various ways in which the principle of the invention may be used.

In the drawings:

Fig. 1 is a part-sectional, side-elevational view of our petroleum treating apparatus.

Fig. 2 is a fragmentary, part-sectional top plan view thereof, the upper stays etc. being omitted.

2

Fig. 3 is a detail inverted plan view of the rotatable shell.

Fig. 4 is a vertical, sectional view of the shell.

Fig. 5 is an enlarged, plan view showing the

cover plate for the sludge sump.

The apparatus herein described is adapted for treatment of various liquids, but for the purpose of illustration, we will describe it as used in the treatment of crude petroleum.

10 Referring now to the drawings in which we have shown the preferred embodiment of our invention. The apparatus comprises a tank or basin 6 into which the crude petroleum from a well (not shown) is piped, through inlet pipe 15 as usual.

A centrally disposed sludge sump S is provided in said basin, and a perforated plate 8 forms a cover therefore, a sludge pipe 9 being connected thereto and is provided with a valve 10 to control the release of sludge therefrom when desired said pipe leading to any desired spot or receptacle (not shown).

A cylindrical shell 11 is mounted in the basin 6, the ends of the shell being flanged as at 12, 25 and top and bottom cover plates 13 and 14 respectively are connected thereto by means of bolts 15, gaskets 16 being interposed as usual to form a leak-proof connection thereto.

Hubs 17 are provided on the top and bottom plates 13 and 14, and a centrally disposed sleeve 18 is mounted in said shell and extends into said hubs, a shaft 19 being mounted in the sleeve and is journaled in bearings 20 and 21 respectively, the bearing 20 being carried by the side wall of the basin and the lower bearing 21 is mounted on a fabricated frame 22 disposed directly above the sump. The shaft and sleeve are secured to the hubs 17 for rotation with the shell, and a pulley 23 is provided on the upper end of the shaft 19 and is connected to any suitable source of power (not shown) in any desired manner.

Circumferentially disposed, vertically spaced outlet pipes 24, 25, and 26 open into the shell 11 at different zones or levels, these pipes discharging into troughs 27, 28, and 29 supported from the wall of the tank 6 as the apparatus is operated, and pipes H lead to receptacles or tanks (not shown) in which the separated products are stored or otherwise disposed of.

50 A plurality of separating disks 30 are mounted on the sleeve 18 in vertically spaced relation, and radially disposed ribs 31 are provided on the upper face of each disk. Openings 32 are provided in each disk between said ribs, so that liquid may flow therethrough, these disks being fixed on

3

the sleeve 18, so that the openings 32 are in vertical alignment, and the outer periphery of each disk is spaced a predetermined distance from the wall of the shell as shown.

A plate 33 divides the shell into individual compartments A and B, and is rigidly connected to the wall of the shell 11, and it, too, is provided with openings R to admit liquid to the space above said plate, which space is designated as zone B.

Funnel-shaped scoop members 34 are connected to pipes 35 which open into the shell 11 through the bottom plate 14, these members being circumferentially spaced to scoop up the crude petroleum as the shell is driven to force it into the shell, and these scoops are vertically spaced with relation to each other so that the path of travel overlaps.

The separating disks aid in separating the brine and impurities from the oil, so that the oil is forced upwardly through the openings 32 provided in the disks 30; whereas, the brine and other impurities are thrown outwardly (due to differences in the specific gravities), and against the wall of the shell.

The operation of the apparatus is substantially as follows:

When power is applied to the pulley 23, the shell 11 will be driven at a predetermined R. P. M., the funnel-shaped scoops 34 scooping up the crude petroleum in the tank and forcing it into the interior of the shell, the centrifugal action tending to separate and break up the oil, brine and impurities, forcing the brine and impurities toward the outer wall of the shell, while the lighter, volatile oil remains in the center, rising upwardly through the openings 32 and thence through openings R into zone B, thence overflowing through outlet pipe 24 and into the circular trough 27 from which it flows through pipe H to an oil receptacle (not shown).

Likewise, the centrifugal action forces the brine and other impurities upwardly and outwardly in the shell, and this is discharged through outlet pipe 25 into the trough 28 from which it is again piped back for further treatment or otherwise disposed of. The outlet pipe 26 operates in substantially the same manner as the pipe 25, and this, too, leads to a trough 29 and thence is disposed of as desired.

All of the discharge pipes 24, 25, and 26 are provided with valves 31 so that the flow can be regulated to suit the nature of the petroleum being processed, and it will of course, be obvious that it may be necessary to re-circulate some of the brine in which there remains sufficient oil to warrant recovery.

A suitable opening 38 is provided in the upper cover plate 13 to facilitate access to the interior of the shell for the purpose of adjustment or repair, and this is closed by means of a plate 39 as usual.

It will of course be obvious that the petroleum may be introduced into the shell by other means than the funnel-shaped scoops, but this is, however, immaterial as any practical means may be employed.

Baffles 40 are provided in the tank 6 to break up and retard the swirling of the tank contents when the apparatus is in operation, and this, of course, may be accomplished in any other manner.

4

From the foregoing description, it will be obvious that we have perfected a very simple, practical, economical, and efficient crude petroleum treating apparatus which separates the brine and other impurities from the oil, so that final cracking and refining can be easily accomplished.

What we claim is:

1. An apparatus for separating liquids of different specific gravities which comprises a driven shell having a centrally disposed shaft, a tank in which the shell is mounted, bearings in said tank and in which the shaft is journaled, a plurality of separating disks of uniform shape and diameter mounted on said shell in superimposed relation, radially disposed ribs on the upper face of said disks, and spaced-apart openings in said disks intermediate said ribs, a separator plate above said disks and dividing the shell into individual vertical zones, openings in said separator plate for connecting said zones, vertically spaced troughs on the inner wall of the tank, outlet pipes on said shell and discharging the separated liquids into said troughs, means connected to the lower end of the driven shell and opening into the lower end of said tank for forcing the liquid to be separated into said shell as the shell is driven, and means for retarding swirling action of the liquids in said tank.

2. An apparatus as set forth in claim 1 in which the tank surrounds said shell and forms a liquid basin for the liquid to be separated, and vertically spaced, funnel-shaped scoops extending into the liquid in said tank for forcing liquid to be separated into the lower end of the shell as said shell is driven.

3. The combination as defined in claim 1 in which vertically spaced, downwardly projecting, funnel-shaped scoops are provided on the lower end of the shell, and the swirl-retarding means comprises a plurality of vertically disposed baffles on the wall of the tank for retarding the swirling action of the crude petroleum therein as the funnel-shaped scoops are driven.

4. The combination defined in claim 1 in which each separating disk bears on the ribs of the next lowest disk.
